METHOD OF MAKING KEY BLANKS

Carl J. Demrick, Birmingham, Mich., assignor to Avis Industrial Corporation, Almont, Mich., a corporation of Delaware

Filed June 8, 1962, Ser. No. 201,047

9 Claims. (Cl. 76—110)

The present invention relates to methods of making workpieces, such as key blanks. In the making of key blanks for padlocks, automobile door and trunk compartment locks, and the like, it is conventional practice to form key blanks by initially performing a blanking operation on sheet metal stock, and thereafter milling operations are performed on the stem of the key blank followed by appropriate embossing operations. Suitable plating operations may then be performed if desired, and the blank is then in condition to have individual biting operations performed so that the key will fit a particular lock. In carrying out manufacturing operations of this type, a substantial amount of sheet metal is converted to scrap by the initial blanking operation. In normal blanking operations it is found that as much as 25% of the metal stock becomes scrap. The number of key blanks of the character described above that are normally manufactured per day in the United States may run into six or even seven figures, so that it will be realized that a very substantial amount of scrap metal results from the present key blank forming operations. Furthermore, when it is kept in mind that the raw materials comprise the major portion of the costs of a key blank, it will be appreciated that there is a need for an improved method of making key blanks which will eliminate this large amount of scrap metal.

It is the principal object of the present invention to provide an improved method of manufacturing workpieces, such as key blanks and the like, which method utilizes substantially all of the material provided for making the key blanks and which eliminates formation of any scrap material during this operation.

It is another object of the present invention to provide a method of making a workpiece of the foregoing character which includes as an initial step of the operation a forming step which produces a preliminary blank containing metal equal to the weight of the finished key blank and wherein the metal is distributed along the axis of the preliminary blank generally in proportion to the metal as it exists in the finished key blank.

It is another object of the present invention to provide a method of making a workpiece of the foregoing character wherein the initial step set forth above comprises sintering powdered metal in the general form of the preliminary blank.

It is another object of the present invention to provide a method of making a workpiece of the foregoing character wherein the initial step of operation comprises cold heading metal wire stock to the configuration of the preliminary blank.

Still another object of the present invention is to provide a method of forming a workpiece of the foregoing character wherein the preliminary blanks defined in the preceding objects, are cold worked by a pressing operation which causes the metal of the preliminary blank to flow to the configuration of the key blank.

It is another object of the present invention to provide a method of manufacturing key blanks and the like which is characterized by the low cost of producing the key blanks and in which the finished product is characterized by the high quality in details of embossments formed in the key blank and in the accurate configuration thereof.

Other objects of this invention will appear in the fol-

2

lowing description and appended claims, reference being had to the accompany drawings forming a part of this specification wherein like reference characters designate corresponding parts in the several views.

5 In the drawings:

FIGURE 1 is a cylindrical wire blank cut from wire stock for use in carrying out one of the methods embodying the present invention for making key blanks;

10 FIGURE 2 is a side view of the wire blank of FIGURE 1 after a cold heading operation has been performed on the same;

FIGURE 3 is a front elevation of a preliminary blank formed by a sintering operation of powdered metal;

15 FIGURE 4 is a front elevation of a key blank formed by the present invention from either of the preliminary blanks shown in FIGURES 2 or 3;

FIGURE 5 is a rear elevation of the key blank illustrated in FIGURE 4;

20 FIGURE 6 is a fragmentary elevational view of a punch and die set that may be used for converting either of the preliminary blanks shown in FIGURES 2 and 3 to the finished blank shown in FIGURES 4 and 5;

FIGURE 7 is a sectional view taken on the line 7—7 of FIGURE 6;

25 FIGURE 8 is a fragmentary bottom elevation of the punch illustrated in FIGURE 6; and

FIGURE 9 is a fragmentary top elevation of the die shown in FIGURE 6.

30 Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

35 Referring now to the drawings, the present invention will be described first with respect to the steps of operation wherein the key blank is made from the wire blank 10 illustrated in FIGURE 1. The blank 10 may be formed from any suitable material that can be cold formed, and for the purposes of making key blanks, the material may be brass, bronze, lead, aluminum, copper, and the like. In cutting the wire blank 10 to its proper length, it is important in carrying out the present invention that the length be such that said wire blank 10 has the same weight of metal as will be found in the finished key blank, thus assuring that there will be no waste of metal resulting from scrap. The wire blank 10 is then passed through one or a series of dies where cold forming operations take place to convert the wire blank 10 to the shape of the preliminary blank 12 shown in FIGURE 2. In carrying out this latter operation, it is important that the preliminary blank 12 be converted to a shape wherein the different frusto-conical or cylindrical portions 14, 16 and 18 thereof conform generally in cross-sectional area to the corresponding cross-sectional areas of the finished key blank 20 shown in FIGURES 4 and 5. Thus, it can be seen that the amount of metal in the frusto-conical portion 14 conforms generally to the amount of metal found in the portion 22 of the finished key blank, and it will be noted that the metal in the portion 14 is distributed along the longitudinal axis of the preliminary key blank 12 in generally the same proportion as is found in the portion 22 of the finished key blank 20. It will also be noted that the same condition exists between the cylindrical portions 16 and 24 and the corresponding portions 18 and 26.

40 45 50 55 60 65 70 75 80 85 90 Following the step of forming the wire blank 10 to the shape of the preliminary blank 12, the preliminary

blank 12 is cold worked or pressed to cause the metal in the preliminary blank 12 to flow to the finished configuration of the key blank, such as is illustrated in FIGURES 4 and 5.

If desired, when carrying out the present invention, other procedures may be used in making the preliminary blank from which no scrap metal results. Thus, a preliminary blank 28, such as is shown in FIGURE 3, may be made by an operation involving sintering powdered metal. In carrying out this operation a metal powdered mixture is fed through a hopper and carefully metered into a die cavity having generally the shape of the blank 28 where the mixture is compressed under high pressure to form a green compact. The green compact is then ejected from the die cavity, placed on a conveyer of a sintering furnace where the powdered particles are bonded together. In this sintering operation the compact is heated to an elevated temperature somewhat below the temperature of the major ingredients and a relatively soft and somewhat porous compact is formed. When removed from the furnace the preliminary blank 28 will have the shape shown in FIGURE 3, and it is to be noted that the portions 30, 32 and 34 have substantially the same amount of metal therein as is found in the portions 22, 24 and 26 of the finished key blank 20. It is also to be noted that the metal in each of the portions 30, 32 and 34 is distributed along the longitudinal axis of preliminary blank 28 substantially the same as is found with respect to the distribution of the metal in portions 22, 24 and 26 of the finished key blank 20. While not shown in the drawings, it is to be understood that the preliminary blank 28, because of its porous condition will be somewhat thicker than the finished key blank 20.

The cold working of either of the preliminary blanks 12 or 28 can be performed in the same punch and die set, such as is illustrated in FIGURES 6-9 of the drawings to which reference is now made. As shown in FIGURE 6, the punch 36 is mounted for vertical reciprocal movement on the posts 38 and the die 40 is held stationary and has a cavity for receiving the punch 36. As seen in FIGURE 9, the die 40 has a cavity 42 conforming to the outer configuration of the key blank 20 and the punch 36 has a configuration, shown in FIGURE 8, for penetrating the cavity 42. The lower face of the punch 36 is shaped to define in the upper surface of the blank 20 the impressions shown in FIGURE 4, and the upwardly facing wall of the cavity 42 is shaped to define in the lower surface of the key blank 20 the impressions shown in FIGURE 5. Thus, the key blank 20 shown in FIGURES 4 and 5 can be obtained by using the punch and die set 36, 40 merely by inserting a preliminary blank, such as are shown in either FIGURES 2 or 3 of the drawings, into the cavity 42 and thereafter squeezing such preliminary blanks 12 or 28 to cause the metal to flow to the final shape of the key blank shown in FIGURES 4 and 5.

When starting with bar stock and forming a preliminary blank 12, it may be necessary to perform one or more annealing operations. Thus, if the blanks 12 were made from brass, it normally would be necessary to anneal the preliminary blank 12 before performing the cold forming operation in the punch and die set 36, 40. Also if the preliminary blank 12 were made for example from aluminum, the annealing operation between the cold heading and cold forming operations described above would be eliminated but a heat treating step would be performed to harden the finished key blank following the cold forming operation in the punch and die set 36, 40.

Such heat treating operations can be eliminated completely in such instances as when the preliminary blank is made from powdered brass, by sintering operations described above resulting in the formation of the preliminary blank 28. In this latter operation, the preliminary blank 28 will be in a relatively porous state and will be readily susceptible to a cold working operation such as

has been described with respect to the punch and die set 36, 40, and such cold working will further compress, harden and strengthen the finished key blank.

Not only will the present invention result in the complete elimination of scrap metal in the making of the key blanks, but it will enable key blanks to be formed having more precise and detailed dimensions and embossments. Still further, this method of operation completely eliminates the need for some of the machine operations which heretofore were required, such as milling operations to form the grooves 44 and 46, which grooves can be seen in FIGURES 4 and 5 on the upper and lower surfaces of the key blank 20.

If desired, the key blank 20 can be plated or it can be used immediately in the form from which it is removed from the punch and die set 36, 40. The only other operations that must be performed on the key blank 20 to make it usable with a conventional lock are the standard biting operations that must be performed to make a key fit a particular lock.

Having thus described my invention, I claim:

1. The method of making a key blank which has various transverse cross-sectional areas along its longitudinal axis comprising the steps of forming a preliminary blank having material equal in weight to that of the finished key blank with the material distributed along the axis of the preliminary blank in cross-sectional areas thereof generally in proportion to corresponding transverse cross-sectional areas of the key blank, placing the preliminary blank in the cavity of a punch and die set which defines the configuration of the said key blank and which has the longitudinal axis of the defined configuration normal to the path of movement of the punch of said set, and cold working said preliminary blank by exerting forces on the preliminary blank with the punch of said set in a direction normal to said longitudinal axis to flow the material of said preliminary blank in the planes of said cross-sectional areas generally laterally with respect to such axis to the final configuration of said key blank.

2. The method of claim 1 wherein the step of forming the preliminary blank includes compacting a powder mix of said material to a green compact having the general shape of said preliminary blank, and thereafter sintering the green compact.

3. The method of claim 1 wherein the step of forming the preliminary blank includes cutting a wire blank which has the same weight as the desired key blank, and cold heading the wire blank to the shape of said preliminary blank.

4. The method of making a brass key blank which has various transverse cross-sectional areas along its longitudinal axis comprising the steps of cutting from brass wire stock a wire blank having the weight of said key blank, forming a preliminary blank from said wire blank by cold working said wire blank until the material is distributed along the longitudinal axis thereof generally in proportion to the cross-sectional areas of said key blank, annealing said preliminary blank, placing the annealed preliminary blank in the cavity of a punch and die set which defines the configuration of said key blank and wherein the longitudinal axis of the configuration is perpendicular to the path of movement of the punch of said set and striking the annealed preliminary blank with the punch of said set in a direction normal to said longitudinal axis to flow the metal of said annealed preliminary blank generally in the planes of said cross-sectional areas to the configuration of said key blank.

5. The method of making an aluminum key blank which has various transverse cross-sectional areas along its longitudinal axis comprising the steps of cutting aluminum wire stock from a wire blank having the weight of said key blank, forming a preliminary blank from said wire blank by cold working said wire blank until the material is distributed along the longitudinal axis thereof generally in proportion to the cross-sectional areas of said

key blank, placing the preliminary blank in the cavity of a punch and die set which defines the configuration of said key blank and wherein the longitudinal axis of the configuration is perpendicular to the path of movement of the punch of said set, engaging the preliminary blank with the punch of said set to flow the metal of said preliminary blank generally laterally in the planes of said cross sectional areas to the configuration of said key blank, and heat treating said key blank to harden the same.

6. The method of making a metal key blank which has various transverse cross-sectional areas along its longitudinal axis comprising the steps of measuring in weight an amount of powder of said metal corresponding to the weight of said key blank, compressing the measured powder to a green compact having a shape conforming generally to the shape of said metal key blank, sintering said green compact, placing the sintered compact in the cavity of a punch and die set which defines the configuration of said metal key blank and in which cavity the longitudinal axis of the configuration is perpendicular to the path of movement of the punch of said set, and cold working the sintered compact with the punch of said set by movement of the punch in such path to flow the metal of the sintered compact generally laterally in the planes of said cross sectional areas to the configuration of said metal key blank.

7. The method of making an elongated metal key blank which has various transverse cross-sectional areas along its longitudinal axis, comprising the steps of forming a pre-

5

liminary blank having the same weight of metal as said key blank and having said material distributed along the longitudinal axis of said preliminary blank generally in proportion to said transverse cross-sectional areas of said key blank, and cold working said preliminary blank

10 to the dimensions of said key blank.

8. The method of claim 7 wherein the step of forming the preliminary blank includes compacting a powder mix of said metal to a green compact, and thereafter sintering the green compact.

15 9. The method of claim 7 wherein the step of forming the preliminary blank includes cutting a wire blank which has the same weight as the desired metal workpiece, and cold heading the wire blank to the shape of said preliminary blank.
